CLAIM

The ornamental design for a device for monitoring and controlling personal lifestyle, as shown and described.

DESCRIPTION

FIG. 1 is a perspective view of an embodiment of a device for monitoring and controlling personal lifestyle showing the new design

FIG. 2 is a right side view thereof;

FIG. 3 is a bottom view thereof;

FIG. 4 is a left side view thereof;

FIG. 5 is a front view thereof;

FIG. 6 is a back view thereof; and,

FIG. 7 is a top view thereof.

The broken lines in the drawings are for the purpose of illustrating unclaimed portions of the device for monitoring and controlling personal lifestyle and form no part of the claimed design.

1 Claim, 7 Drawing Sheets

Related U.S. Application Data

a continuation of application No. 29/734,491, filed on May 13, 2020, now Pat. No. Des. 951,786, which is a division of application No. 29/649,333, filed on May 29, 2018, now Pat. No. Des. 884,502.
